UNITED STATES PATENT OFFICE.

JONATHAN FORCE, OF LIVINGSTON, NEW JERSEY, ASSIGNOR TO GENERAL ELECTRIC COMPANY, A CORPORATION OF NEW YORK.

ARC DEVICE.

Application filed March 1, 1922. Serial No. 540,276.

The present invention relates to devices in which an arc is operated in a gaseous atmosphere between electrodes of which either the negative electrode alone, or both electrodes, operate at incandescence.

It is the object of my invention to improve the operation and life of an incandescent electrode device. In accordance with one of the features of my invention, the

10 trouble which is sometimes experienced due to the arc playing between the leading-in conductors during starting is obviated. As these conductors are not adapted to serve as electrodes they are sometimes fused and 15 in many cases the seals are cracked by the arc traveling to the point of entry of the conductors into the bulb. Other features of my invention, for example, the reduction of 20 flickering and the suppression of electrode disintegration, are hereinafter described.

I have discovered that when a section of the current conveying conductor adjacent the cathode is associated with a material having a higher electron emissivity than 25 the rest of the conductor that then the arc will be confined to the electrodes.

The accompanying drawing illustrates in Fig. 1 one embodiment of my invention in longitudinal section; Fig. 2 illustrates a 30 modification; and Figs. 3, 4 and 5 illustrate different starting devices applied to lamps embodying my invention.

The device shown in Fig. 1 is particularly 35 intended to operate as a lamp and therefore, the electrodes 1, 2 are of substantially equal size, both electrodes consisting of a refractory metal, preferably tungsten, and both ordinarily being operated at bright incandescence. These electrodes are carried by 40 conductors, 3, 4, which may also consist of tungsten, and are sealed into the envelope 5, which consists of glass having substantially the same coefficient of expansion as tungsten. The tins 6, 7 of the conductors 3, 4 are bent at an angle to the rest of the conductors and toward each other so as to 45 make the gap between the juxtaposed electrodes 1, 2 shorter than the distance between the conductors 3, 4. The envelope 5 contains a gaseous or gasifiable material which at 50 the operating temperature of the lamp has a pressure high enough to cause an electrical discharge between the electrodes 1, 2 to be-

come concentrated and assume the characteristics of an electric arc, the energy of the 55 discharge being enough to heat the electrodes to incandescence. For example, the bulb may contain a quantity of mercury 8 and a filling of an inert gas such as argon, or nitrogen. The wires 3, 4 are insulated 60 from the mercury by insulating coatings 9, 10 of glass or the like.

The container or bulb 5 ordinarily is elongated to provide a condensing space above the arc. Preferably there is provided a 65 separate chamber 11 connected to the main condensing chamber 13 by a constricted orifice 12 which is in line with the trajectory of the blast of mercury vapor emanating from the arc between the electrodes 1, 2. The 70 mercury vapor blast enters this auxiliary chamber 11, where the vapor pressure is determined by the temperature of the walls of the auxiliary chamber. This chamber therefore, functions to regulate the gaseous pressure about the electrodes.

In order to prevent electrode disintegration during the operation of the arc, the parts of the device must be arranged and proportioned to enable the arc to operate with a voltage consumption below a limiting value depending on the character of the device, particularly the length of the arc. One of the conditions controlling the voltage drop between the electrodes is the pressure of the gas or vapor in which the arc operates. By the addition of the chamber 11, the pressure may be maintained at a lower value. Consequently the arc will be stabilized at a lower voltage and the disintegration of the electrodes will be largely suppressed.

The auxiliary chamber should be proportioned to maintain the gas in the device at a pressure which is neither so high as to cause an increase of the arc gap by disintegration of the electrodes nor so low as to cause building out of the electrodes, and decrease of arc gap. Too small a chamber increases the pressure and too large a chamber causes too much condensation and decreases the pressure. The constriction or throat 12 should not be so small as to interfere with the return of condensed mercury nor so large as to admit so much mercury vapor that the chamber runs abnormally hot. In Patent

No. 1,578,973, issued March 30, 1926, I have made claims on the bulb structure shown in Fig. 1.

At the end of the straight portions of the conductors 3, 4 and adjacent the electrodes 1, 2 are located particles 14, 15 of a material having a higher electron emissivity than the lead wires. For example these beads may consist of tungsten containing thorium, or of 10 metallic thorium, or an alloy of thorium. I prefer to use tungsten containing about 5% thorium. This material may be prepared as described in Coolidge Patent 1,082,933. The thoriated tungsten mass may be welded 15 as a bead, or a short length of wire to the lead wires.

In some cases a short section of the lead wires, say, one-half inch, adjacent the electrode stems 6, 7 may consist of thoriated 20 tungsten. Such a construction is shown in Fig. 2 which illustrates a somewhat modified arc device in which the lead wires 3, 4, project downwardly through a condensing chamber 13' instead of projecting through 25 the mercury. The sections 16, 17 of the lead wires consist of thoriated tungsten.

In the devices illustrated in Figs. 1 and 2 both electrode leads are provided with thoriated tungsten for localizing the arc to permit 30 operation with alternating current. When an incandescent arc device is intended for operation with direct current, the cathode conductor only need be provided with a material of high electron emissivity.

35 When a device constructed in accordance with my invention is placed into operation, for example, by producing a high potential discharge between the electrodes 1, 2, the arc starts from the thoriated particles, 14, 15, 40 remains there for a short time until the electrodes, 1, 2 become heated, and then because of the spatial relation of the electrodes to the thoriated particles, the arc will jump to the electrodes where it continues to steadily 45 operate.

When the arc has once been started between the electrodes 1, 2 and therefore, has heated these electrodes to incandescence, 50 there is little or no tendency for the arc to desert the electrodes, but in the absence of the thoriated masses, the arc would tend to flicker. The high electron emission from the thoriated tungsten counteracts this tendency and promotes a smooth, steady operation of 55 the arc.

Although the arc may be started by a high voltage discharge it is desirable in many cases to start the arc by a low-voltage auxiliary discharge. For example, I have 60 illustrated in Fig. 3 an arc device in which two conductors 20, 21 depend from the electrode conductors and dip into the mercury body 8. These conductors 20, 21 are near enough to the gap between the electrodes 65 1, 2, to ionize the gas in the gap.

The mercury communicates through a tube 22 with an auxiliary chamber 23 containing a gas at the same pressure, or approximately so, as the gas in the main bulb 5. When current at suitable voltage is impressed upon the conductors 3, 4 the conductors 20, 21 become incandescent and the arc starts between the electrodes. As the gas or vapor pressure builds up in the bulb 5, some of the mercury therein is pushed out 70 through the tube 22 into the bulb 23, thereby breaking the circuit through the conductors 20, 21.

In Figs. 4, 5 I have illustrated devices embodying my invention having conductors 24, 25 connected to the electrode conductors 6, 7 and extending downwardly at such an angle that a circuit may be completed between these conductors 24, 25 by tilting the bulb, as shown in Figs. 4 and 5 by full lines. 80 When the lamp is tilted back slowly toward the position indicated by dotted lines, auxiliary arcs are formed at the terminals of the conductors 24, 25 with the mercury, thereby starting the main arc between the electrodes 1, 2. A restoration of the bulb to an upright position causes these starting arcs to lengthen and break.

What I desire to secure by Letters Patent 90 of the United States, is:—

1. A gas ionization device provided with refractory electrodes spaced apart during starting and having in combination with said electrodes, a material of higher electron emissivity than said electrodes and associated with said electrodes in such spatial relation that an electric discharge initiated from said material will be transferred to said electrodes. 100

2. An electrical discharge device comprising the combination of a container, current-carrying conductors sealed into said container, electrodes consisting of refractory material supported by said conductors and located adjacent each other with an intervening gap, and a quantity of thorium material associated with at least one of said conductors in such position relative to the electrode supported by said conductor that an arc when started from said material will be 110 transferred to said electrode. 115

3. An electric discharge device which is provided with an ionizable medium and containing refractory electrodes mounted upon conductors bent at such angle with respect to each other that said electrodes are spaced apart a shorter distance than said conductors, and a quantity of material containing thorium as an elementary constituent applied to one or more of said conductors at a region spaced away from the electrode mounted thereon. 120

4. An arc device comprising the combination of a container, conductors sealed into said container bearing cooperating elec- 125

- trodes, a gas or gasifiable material in said container capable of giving a discharge between said electrodes an arc-like characteristic and a material capable of evolving thorium applied to one of said conductors in such position that an arc passing from said material to the cooperating electrode will heat the electrode borne upon the conductor on which said material is applied and will thereby facilitate the starting of an arc from said electrode.
5. An arc device comprising the combination of a container, electrodes therein for supporting an arc, current supply conductors for said electrodes and means for increasing the electron emissivity of one of said conductors at a region adjacent to the electrode carried by said conductor, said means being so positioned with respect to the cooperating electrode that arc started by said means will operate between said electrodes.
6. An arc device charged with gas at substantial pressure containing electrodes of refractory material, stems fixedly supporting said electrodes out of electrical contact with each other, and a medium capable of becoming the seat of an arc more readily than said supporting stems and electrodes mount-
- ed in such position on said stems that an arc started therefrom will be transferred to said electrodes.
7. An arc device comprising the combination of a bulb, electrodes therein consisting of tungsten, electric conductors therefor, a quantity of thoria associated with said conductors adjacent said electrodes, and a quantity of mercury in said bulb, and means cooperating with said mercury to start an arc between said electrodes.
8. An electric arc lamp comprising a sealed bulb, a gas or gasifiable material therein which will have during operation of said device a substantial pressure, current supply conductors mounted in fixed relation in said bulb, the end portions of said conductors extending toward each other in a plane substantially at right angles to the remaining portion thereof, electrodes of refractory material affixed to the tips of said conductors, and a quantity of material of higher electron emissivity than said electrodes affixed to said conductors in the plane of said end portions and spaced away from said electrodes.
- In witness whereof, I have hereunto set my hand this 25th day of February 1922.
- JONATHAN FORCE.
